PERMEABLE BREAKWATER

Harvey J. Humphrey, Cleveland, Ohio

Application September 9, 1946, Serial No. 695,703

9 Claims. (Cl. 61—4)

1

This invention relates to a breakwater and more particularly to a permeable breakwater so called because it is provided with openings through which the water may pass.

The broad object of the invention is to provide a breakwater which will prevent beach or bank erosion and will cause sand suspended in the water to be deposited therefrom upon the bottom and thus build up and maintain the beach or bank.

In moving water, such as waves, usually there are suspended particles of sand. Also the waves which have rolled on the beach and are receding therefrom carrying with them an appreciable amount of suspended beach sand.

A more particular object of the invention is to provide a breakwater which while allowing waves to pass therethrough slows down the movement of the waves to an extent such that the sand suspended in the water is dropped therefrom and deposited upon the bottom.

Another object is to provide a breakwater that is constructed of identical or substantially identical units and each of which is so formed as to be self-seating and anchored in its position in the breakwater.

A further object of the invention is to provide a breakwater which presents irregular surfaces to the action of the waves and thereby lessens the tendency of the waves to undermine the breakwater.

Further and additional objects and advantages not hereinbefore referred to will become apparent during the detailed description of several embodiments of the invention which is to follow.

Referring to the accompanying drawings:

Fig. 1 is a plan view of one form of breakwater embodying the invention and extending between two jetties or piers projecting outwardly from the beach or bank.

Fig. 2 is a perspective view of one of the identical units employed in building the breakwater.

Fig. 3 is a sectional view through the unit shown in Fig. 2 and is taken substantially on line 3—3 of Fig. 2 looking in the direction of the arrows.

Fig. 4 is a fragmentary sectional view of one corner of the unit shown in Fig. 2.

Fig. 5 is a plan view similar to Fig. 1 but showing a modified form of breakwater and identical units used in its construction from those shown in Fig. 1, with the breakwater of Fig. 2 also embodying the invention, and

Fig. 6 is a perspective view of one of the identi-

2

cal units employed in the construction of the breakwater in Fig. 4.

In describing the breakwater illustrated in Fig. 1 the construction of the identical units forming the breakwater will first be set forth.

In this form of the invention the identical units forming the breakwater are indicated in their entirety by the numeral 10 and comprise substantially rectangular hollow blocks open at their tops and bottoms. The units 10 preferably are constructed of concrete poured into suitable forms as will be well understood in the art. The side walls 11 and the end walls 12 of the units are provided with a plurality of openings 13 extending completely through the walls. Embedded or cast in each corner of the units 10 are pipes or tubes 14a of such length that their ends are flush with the top and bottom ends of the units.

In constructing the breakwater of the units 10 said units may be floated or otherwise transported to the location of the breakwater and into their proper position. Then the tubes or pipes 14 of smaller diameter than the pipes or tubes 14a are inserted through the latter. As an example of the diameters of the tubes 14a and 14, the former may be of five inch diameter and the latter of four inch diameter. The pipes 14 are substantially longer than the height of the unit for a purpose soon to be pointed out. After the tubes or pipes 14 have been inserted in the pipes 14a jets of water are injected into the pipes 14 and said jets cause the lower toothed ends 14b of the pipes 14 to be jetted down into the bottom a suitable depth. As an example, the lower ends 35 of the pipes 14 may extend into the bottom of the body of water in which the breakwater is located a matter of about five feet. When the unit is installed the tubes or pipes 14 will project above the upper end of the unit and can be filled with concrete or cement if desired. Thus the unit is securely anchored in position.

In Fig. 1 the units are shown as assembled into a breakwater which extends between the outer ends of two spaced jetties or piers 15 projecting outwardly from the beach or bank and which may or may not be of permeable type. The outer ends of the jetties 15 are shown (for illustrative purposes only) as of polygonal formation. The units are each arranged at an angle to the short-line and have the inner wall 11 of one unit overlapping the outer wall 11 of the adjacent unit. It will also be noted that the end units of the breakwater contact the sides of the outer ends of the jetties or piers 15.

It will be observed that the offshore side of the

breakwater and, in this instance, also the inshore side thereof presents an irregular surface and in the present illustration surfaces which may be designated as saw tooth surfaces. This is an important consideration as it lessens the tendency of the waves which strike the breakwater to undermine or wash out the bottom beneath the breakwater, as is so prevalent in breakwaters which present an even, unbroken surface to the action of the waves.

Irrespective of whether the waves strike the breakwater from a direction perpendicular to the shore line or from a direction at an angle thereto, the momentum and action of the waves will be decelerated by the plurality of angularity disposed relatively small surfaces presented throughout the length of the breakwater and hence the force of the waves will have a minimum tendency to undermine the breakwater.

In addition it will be noted that the breakwater does not present a solid obstruction in the path of the waves but due to the openings 13 in the walls of the units the waves can pass through the breakwater. However, the momentum of the waves is substantially reduced in passing through the breakwater and hence particles of sand suspended in the water are caused to drop therefrom and be deposited on the bottom.

In actual practice it has been found that the major portion of the suspended sand particles is not dropped or deposited until the waves have passed completely through the breakwater and hence the interiors of the hollow units do not fill up with deposited sand. It has also been found in actual practice that the breakwater slows down the recession rate of the waves after they have struck the beach and hence any sand which has become suspended in the water rolling on the beach is dropped or deposited between the beach and the shore side of the breakwater.

Therefore, a breakwater constructed in accordance with the present invention not only functions to prevent erosion of the beach or bank, but also operates to build up the beach by the deposit of suspended sand particles from the water of incoming waves.

Another important feature of the breakwater is that the irregular or saw tooth surfaces throughout the length of the breakwater possess great effectiveness in withstanding the pressures of ice floes which so often cause conventional breakwaters to be broken or displaced.

In Figs. 5 and 6 the identical units 16 of the breakwater are shown as having parallel side walls 17 extending perpendicularly to the rear end wall 18 and connected at their outer ends to angularly disposed end walls 19, said latter walls providing the irregular surface of the offshore side of the breakwater. The units 16 when assembled into the breakwater can be so positioned that the inner end walls 18 thereof will be substantially parallel to the shoreline or the units can be positioned in an arc as indicated in Fig. 4.

It will be noted that the side walls 17 of adjacent units are arranged in contact with each other. The units 16 can be anchored and positioned in the breakwater in the same manner as referred to with respect to the units 10 and also it will be understood that the breakwater of Fig. 4 possesses the same advantages and utility as the breakwater of Fig. 1.

Although several preferred embodiments of the invention have been illustrated and described

herein, it will be understood that the invention is susceptible of such modifications and adaptations as fall within the scope of the appended claims.

Having thus described my invention, I claim:

1. A breakwater comprising a series of polygonal hollow integrally formed blocks anchored with a wall of each block in contacting overlapping engagement with a wall of an adjacent block, said blocks being offset with respect to each other to provide a serrated frontal surface, each of said blocks being provided in the walls thereof with a plurality of openings wherefore waves striking the breakwater can pass therethrough but will have their momentum decelerated to cause suspended sand particles to be deposited on the bottom of the body of water in which the breakwater is located.

15 2. A breakwater comprising a series of polygonal hollow integrally formed blocks anchored with a wall of each block in contacting overlapping engagement with a wall of an adjacent block, each of said blocks being provided in the walls thereof with a plurality of openings wherefore waves striking the breakwater can pass therethrough but will have their momentum decelerated to cause suspended sand particles to be deposited on the bottom of the body of water in which the breakwater is located.

20 30 3. A breakwater comprising a series of polygonal hollow integrally formed blocks anchored with a wall of each block in contacting overlapping engagement with a wall of an adjacent block, said blocks being offset with respect to each other to provide a serrated frontal surface, each of said blocks being provided in the walls thereof with a plurality of openings wherefore waves striking the breakwater can pass therethrough but will have their momentum decelerated to cause suspended sand particles to be deposited on the bottom of the body of water in which the breakwater is located, said units being offset with respect to each other so that the offshore side of the breakwater presents an irregular or serrated surface.

35 40 45 50 3. A breakwater comprising a series of polygonal hollow integrally formed blocks anchored with a wall of each block in contacting overlapping engagement with a wall of an adjacent block, said blocks being offset with respect to each other to provide a serrated frontal surface, each of said blocks being provided in the walls thereof with a plurality of openings wherefore waves striking the breakwater can pass therethrough but will have their momentum decelerated to cause suspended sand particles to be deposited on the bottom of the body of water in which the breakwater is located, each of said blocks being provided in the corners thereof with pipes extending below the bottom end of the block into the bottom of the body of water and filled with cement or similar material after the block has been positioned in the breakwater.

55 60 65 70 75 4. A breakwater comprising a series of polygonal hollow integrally formed blocks anchored with a wall of each block in contacting engagement with a wall of an adjacent block and spaced piers projecting outwardly from the shore and with the end blocks of the series contacting said piers and said series extending between said piers, said blocks being offset with respect to each other to provide a serrated frontal surface, each of said blocks being provided in the walls thereof with a plurality of openings wherefore waves striking the breakwater can pass therethrough but will have their momentum decelerated to cause suspended sand particles to be deposited on the bottom of the body of water in which the breakwater is located.

5. A breakwater comprising a series of rectangular hollow blocks anchored in position and arranged with their long sides at an angle less than perpendicular to the shore line and with the adjacent long sides of the blocks in partially overlapping contact with each other wherefore both the offshore and inshore sides of the breakwater present irregular surfaces, each of said blocks being provided in the walls thereof with

a plurality of openings wherefore waves striking the breakwater can pass therethrough but will have their momentum decelerated to cause suspended sand particles to be deposited on the bottom of the body of water in which the breakwater is located.

6. A breakwater comprising a series of polygonal hollow integrally formed blocks anchored in contacting engagement with each other, said blocks having a straight end wall and a pointed end wall and being arranged with the latter located in the offshore direction to present an irregular surface, said blocks being provided in the walls thereof with a plurality of openings wherefore waves striking the breakwater can pass therethrough but will have their momentum decelerated to cause suspended sand particles to be deposited on the bottom of the body of water in which the breakwater is located.

7. A breakwater as defined in claim 6 and wherein the series of blocks extend between and are in contact with spaced jetties projecting from the shore with said series of blocks arranged in an arc.

8. A breakwater comprising a series of polygonal hollow integrally formed blocks arranged to have their adjacent walls in contacting overlapping engagement with each other, spaced piers or jetties projecting outwardly from the shore and with the end blocks of the series contacting the same and said series extending therebetween, said blocks having angularly disposed wall surfaces located outwardly of their overlapping engagement with each other and forming a continuous serrated frontal surface extending between said piers each of said blocks being provided in the walls thereof with a plurality of openings, each of said blocks being provided in the corners thereof with pipes extending below the bottom wall of the block

into the bottom of the body of water in which the breakwater is located and filled with cement or similar material after the block has been positioned in the breakwater.

9. A breakwater comprising a series of polygonal hollow integrally formed blocks arranged to have their adjacent walls in contacting overlapping engagement with each other, spaced piers or jetties projecting outwardly from the shore and with the end blocks of the series contacting the same and said series extending therebetween, said blocks having angularly disposed wall surfaces located outwardly of their overlapping engagement with each other and forming a continuous serrated frontal surface extending between said piers, each of said blocks being provided in the walls thereof with a plurality of openings wherefore surfaces striking the breakwater can pass therethrough but will have their momentum decelerated to cause suspended sand particles to be deposited on the bottom of the body of water in which the breakwater is located, and means for anchoring the blocks in position in said series.
